CLAIM

We claim the ornamental design for a microscope, as shown and described.

DESCRIPTION

FIG. 1 is a perspective view of a microscope of the present invention;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings depict portions of the microscope that form no part of the claimed design.
